(57) **CLAIM**

The ornamental design for a bowl with wave contour, as shown and described.

DESCRIPTION

FIG. 1 is an upper perspective view of a first embodiment of a bowl with wave contour;

FIG. 2 is a lower perspective view of thereof;

FIG. 3 is a side view of thereof;

FIG. 4 is a top view of thereof;

FIG. 5 is a bottom view of thereof;

FIG. 6 is an upper perspective view of a second embodiment of FIG. 1;

FIG. 7 is a lower perspective view thereof;

FIG. 8 is a side view of thereof;

FIG. 9 is a top view thereof;

FIG. 10 is a bottom view thereof;

FIG. 11 is an upper perspective view of a third embodiment of FIG. 1;

FIG. 12 is a lower perspective view thereof;

FIG. 13 is a side view thereof;

FIG. 14 is a top view thereof;

FIG. 15 is a bottom view thereof;

FIG. 16 is an upper perspective view of a fourth embodiment of FIG. 1;

FIG. 17 is a lower perspective view thereof;

FIG. 18 is a side view of the fourth thereof;

FIG. 19 is a top view of the fourth thereof;

FIG. 20 is a bottom view of the fourth thereof;

FIG. 21 is an upper perspective view of a fifth embodiment of FIG. 1;

FIG. 22 is a lower perspective view thereof;

FIG. 23 is a side view thereof;

FIG. 24 is a top view thereof; and,

FIG. 25 is a bottom view thereof.

The broken lines represent features that form no part of the claim. The dot-dot-dash-dot-dot-dash boundary line represents the boundaries of the claim.
